(57) **CLAIM**

The ornamental design for handset packaging, as shown and described.

DESCRIPTION

FIG. 1 is a perspective top view of handset packaging showing our new design;

FIG. 2 is a top view thereof;

FIG. 3 is a bottom view thereof;

FIG. 4 is a right side view thereof;

FIG. 5 is a left side view thereof;

FIG. 6 is a rear view thereof; and,

FIG. 7 is a front view thereof.

The broken lines in the figures represent unclaimed environmental subject matter and form no part of the claimed design.
